AXEL JOHNSON, OF OAKLAND, CALIFORNIA, ASSIGNOR TO AMERICAN CAN COMPANY,
OF SAN FRANCISCO, CALIFORNIA, A CORPORATION OF NEW JERSEY.

APPARATUS FOR DOUBLE-SEAMING COVERS TO CAN-BODIES.

1,317,977.

Specification of Letters Patent.

Patented Oct. 7, 1919.

Application filed January 31, 1918. Serial No. 214,657.

To all whom it may concern:

Be it known that I, AXEL JOHNSON, a citizen of the United States, residing at Oakland, in the county of Alameda and State 5 of California, have invented certain new and useful Improvements in Apparatus for Double-Seaming Covers to Can-Bodies, of which the following is a specification.

The hereinafter described invention relates to an apparatus for hermetically sealing can ends or covers to flanged can bodies for the preservation of food products or other similar materials, and more particularly to the means for double seaming the 10 flange of a can cover to the flanged end of a can body, and the same resides in the improved construction of the can chuck for holding the cover onto the can body during the seaming operation, and in the construction 15 of the seaming roll associated with the chuck for performing the double seaming operation of uniting the flange of the can cover to the flange of the can body; the object of the invention being to secure accuracy of gaging the seaming roll with respect to the can end chuck, whereby the seaming roll will be relieved of the thrust strains usually placed thereon during the 20 double seaming operation. A very slight error in the adjustment of the rolls relative to the can end chuck will result in the 25 formation of an imperfect or leaky seam between the cover and can end after the completion of the double seaming operation, and it is highly desirable to reduce the chances of an occurrence of this result to a minimum, and which in the present case is accomplished by providing a can end chuck with circumferential grooves in 30 the face thereof arranged in different vertical planes, with which coacts successively a circumferential flange outwardly projecting from a double grooved seaming roll, the 35 grooves of which lie in different vertical planes, the said flange of the seaming roll successively engaging with the grooves in the can end chuck as the seaming roll's vertical position is varied to successively place the seaming grooves thereof in radial alignment with the flange of a can end cover to 40 be hermetically double seamed to the flanged end of a can body.

In order to comprehend the invention, reference should be had to the accompanying sheets of drawings illustrating the in- 45

vention as applied to a single spindle double seaming apparatus, wherein—

Figure 1 is a plan view of the apparatus illustrating the means associated with the seaming mechanism for delivering can bodies with ends loosely applied thereto to the said seaming mechanism. 60

Fig. 2 is a vertical sectional elevation taken on line 2—2 of Fig. 1 of the drawings and viewed in the direction of the arrows. 65

Fig. 3 is a top plan view partly broken away taken on sectional line 3—3, Fig. 2 of the drawings, and viewed in the direction of the arrows.

Fig. 4 is a broken detail vertical sectional 70 view of the housing for inclosing the operative means for the seaming mechanism, said view being taken on the sectional line 4—4, Fig. 3 of the drawings, and viewed in the direction of the arrows. 75

Fig. 5 is a sectional plan view taken on line 5—5 of Fig. 2 of the drawings, and viewed in the direction of the arrows.

Fig. 6 is a sectional plan view taken on the irregular sectional line 6—6 of Fig. 2 80 of the drawings, and viewed in the direction of the arrows.

Fig. 7 is a vertical central section of a portion of a can, the chuck and the seaming roll with its lower groove engaged with the 85 can end seam.

Fig. 8 is a similar view with the upper groove engaged with said seam.

In the drawings, and referring more particularly to Fig. 2 thereof, the reference numeral 1 is used to designate any suitable form of a supporting structure capable of sustaining the working parts of the apparatus and which preferably has formed integral therewith the circular housing 2, from 90 which housing depends the tubular sleeve 3 through which projects the vertical shaft 4, which shaft works in upper and lower bearings 5 and 5', the latter bearing being carried by the cover plate 6 of the housing 2. 95

Within suitable bearings of the cover plate 6 is mounted for rotation a horizontally disposed drive shaft 7, which is driven, in the present case, through the medium of a belt wheel 8 mounted on one end thereof, 100 which receives its motion from a drive belt, not illustrated, having power applied thereto by any suitable source of outside supply. On the drive shaft 7 is mounted a gear 9 which meshes with the gear 10 secured to the 110

upper end of the vertical shaft 4, so that the rotation of the drive shaft 7 through the medium of the intermeshing gears 9 and 10 is transmitted to the said shaft 4. To the shaft 4, within the housing 2, is secured in any suitable manner a head 11, which head rotates with the said shaft 4 and at its lower end rests on the anti-frictional ball bearings 12 interposed between the plate 12' secured to the bottom of the head 11 and the plate 18 secured in any suitable manner within the housing and to the bottom wall thereof, the said plates 12' and 18 serving as bearing rings to form a track-way for the anti frictional balls 12, the said head 11 being supported for rotation on the anti-frictional bearings. There is secured to the shaft 4, intermediate the gear 10 and the head 11, an enlarged cog-ring 14, which meshes with the cog pinion 15 secured to the stem 16 of the can head chuck 17, so that the rotary movement of the shaft 4 is transmitted to the stem 16 of the can end chuck 17. The stem of the said chuck works within suitable bearings carried by the housing 2 and within which bearings the stem 16 is vertically movable, the can end chuck 17 being carried by the lower end of the stem 16 projected below the housing 2.

On the stem 16 of the can end chuck 17 and within the housing 2 is located a yoke 18, Figs. 2, 3, 4 and 5 of the drawings, which yoke is held against vertical movement on the stem 16 by means of a collar 19 screwed onto the threaded section 19' of the said stem 16, and the said yoke is held against downward movement relative to the stem 16 by means of the flange 20 formed integral with the said stem 16, there being interposed between the said flange 20 and the yoke 18 the anti-frictional ball bearings 21. The yoke 18 is held against rotation by means of the lateral projections 22 thereof, each of which projections is formed with a vertical bore therethrough which fits over the studs 23 upwardly projecting from the base of the housing 2, Figs. 4 and 5 of the drawings. The yoke 18 is thus permitted free vertical movement with the stem 16, but is held against rotation therewith. From the upper portion of the yoke 18 there is laterally projected a stud 24 which carries an anti-frictional cam following roll 24', which roll works within a cam groove 25 formed in the periphery of the head 11, so that during the rotary movement of the said head 11 the cam groove 25 thereof acts relatively to the roll 24' to raise and lower the yoke 18. As this yoke is held against vertical movement with respect to the stem 16, it is apparent that the said stem is raised and lowered with the vertical movement of the yoke 18.

Adjacent the can end chuck 17 there is located a seaming head 26, which seaming head is mounted upon the lower end of a

spindle 27 journaled for oscillatory and linear movement at 28 of the housing 2, the said spindle 27 carrying at its upper end a transverse double arm 29 (Figs. 2 and 5 of the drawings). The said arm 29 carries upon its ends cam following rollers 30 and 31, the former below and the latter above the said arm, which said following rollers are adapted to follow cams 32 and 33 respectively formed upon the peripheral surface of the rotating head 11 and which cams during the rotary movement of the said head act in conjunction with the rollers 31 and 30 to oscillate the seaming head 26 to place the seaming roll 26' carried thereby into operative relation with the can end chuck 17 for the double seaming of the can end to the can body.

The seaming head spindle 27 also carries a cam following roller 34 which is adapted to lie within and follow an offset groove 35 formed in the rotary head 11 below the cam groove 25 and between the peripheral cams 32 and 33, the said cam groove 35 serving through the medium of the cam following roll 34 to raise and lower the spindle 27 of the seaming head. The seaming head 26 is in the form of a lever extended at right angles from the spindle 27, as shown in Figs. 2 and 6 of the drawings, and carries at its outer end the seaming roll 26', which roll is mounted for free rotation within the bifurcated portion of the said seaming head 26, the said seaming roll being freely rotatable upon a pin 36. The said seaming roll 26' is formed with two adjacent peripheral grooves 38 and 38', Figs. 2, 7 and 8 of the drawings, the lower groove 38' performing the first seaming operation upon the can seam, as illustrated in Fig. 7 of the drawings, and the upper groove 38 performing the final seaming operation thereon, as disclosed in Fig. 8 of the drawings.

The seaming roll 26' is provided with an outstanding circumferential flange 39, which is adapted to move successively into and out of the two adjacent peripheral grooves 40 and 40' formed in the can end chuck 17. As the flange 39 of the seaming head moves within either of the grooves of the can end chuck, the same serves to properly gage the seaming roll relative to the said can end chuck and the grooves 38 and 38' of the said roll in respect to the seam being operated upon thereby. By this means there is an exact gaging of the seaming roll with respect to the can end chuck head and the seaming grooves 38 and 38' of the said roll 29 are accurately positioned relative to the seam to be operated upon.

It will be understood that the engagement of the flange 39 with the grooves 40 and 40' of the can end chuck 17 takes place while the said chuck is in lowered position to hold the can end 41 onto the can body 42 to which it

is to be secured, which body with the end loosely applied thereto at such time is properly positioned relative to the rotatable cam rest 43, Figs. 2, 3 and 8 of the drawings.

5 The can bodies 42 with the ends loosely applied thereto are fed, in the present case, by means of an endless traveling belt 43', Fig. 1 of the drawings, to successively place the can bodies onto the horizontally 10 posed table 44 and within one of the peripheral pockets or cut-outs 45 of the can feed wheel 46, the said can feed wheel acting as a timer to place the advancing cans with the ends loosely applied thereto in timed and 15 spaced relation, the circular portions 47 of the can feed wheel 46 intermediate of the cut-out portions 45 during the advancing of one can serving to act as a guard for holding the cans back until the next following pocket 20 or cut-out 45 engages and advances a can. The cans are thus advanced successively by the pockets 45 of the feed wheel 46 and are guided in their path of travel by a curved extension wall 48, and the said cans as advanced by the carrier wheel 46 are deposited onto the rotatable rest 43 of the table 44, and when so positioned are in axial alignment with the can end chuck 17. The can carrier wheel 46 is mounted on a short vertical shaft 49 extended through a hub 49' of the table 44, the said shaft 49 at its lower extremity carrying a Geneva wheel 50 which is engaged by a roll 51 of an arm 52 secured to and projecting from the shaft 53 working 25 in bearings of the frame 1, and a hub extension 44' of the table 44 (Fig. 2 of the drawings).

Rotation is imparted to the shaft 53 from the drive shaft 4 by means of the intermeshing gears 54 and 54' mounted respectively 30 on the said shafts 53 and 4, while intermittent motion is transmitted to the can carrier wheel 46 from the shaft 53 through the medium of the Geneva mechanism 50, 51 and 35 52, before described.

In the operation of the machine, assuming a can body 42 with an end 41 loosely applied thereto to be positioned on the rotatable can rest 43, the cam following roller 40 50 34 working within the cam groove 25 of the rotary head 11 first acts to lower the stem 16 carrying the can end chuck 17 to cause the same to rest firmly onto the can cover or end 41 and to clamp the same onto the can body 42, the can body at such time 55 with the end clamped thereto rotating freely with the rotary movement of the stem or spindle 28, while the cam following roll 34 working within the cam groove 35 of the driven head 12 acting at the same time to lower the stem 27 of the seaming head 26 to place the flange 39 of the seaming roll 26' in radial alignment with the upper groove 40 of the can head chuck 17. The seaming head 26 is then oscillated by the action of

the cams 32 and 33 of the head 11 to first move the seaming roll radially to place the flange 29 within the gage groove 40 of the can end chuck in order to gage and hold the seaming roll in proper position relative to the said can end chuck and cause the lower groove 38' thereof to properly act onto the seam of the rotating can for initially curling the flange of the can end relative to the flange of the can body. The 70 seaming roll is then moved radially out of engagement with the said seam and is lowered by means of the second action of the cam groove 35 to place the upper seaming groove 38 of the seaming roll 26' into radial alignment with the acted on seam and the flange 39 of said roll into alignment with the lower gage groove 40' of the can end chuck, when the seaming head is again oscillated to place the flange 39 within the gage groove 40' and to cause the second seaming groove 38 to act on the seam for the final operation thereupon for the hermetical sealing thereof, it being understood that during these operations the seaming roll 26' is rotated by frictional engagement of its seaming groove with the can end and the engagement of the flange 39 with the gage grooves of the can end chuck, which chuck with the clamped can end and body 85 is driven at high rotating speed.

After the completion of the seaming operation the seaming head is oscillated or moved radially to take the seaming roll from within the sphere of the can end chuck 100 and the seam of the can, after which the can head chuck is raised by the cam follower roll 24 working within the cam groove 25 and the seaming head is likewise raised by the action of the cam following roll 34 105 working with the cam groove 35.

The parts being thus returned to normal position in readiness to be lowered to clamp a can end to a positioned can body and to double seam the flange of the end of the can body. It will be seen from the foregoing that the seaming roll is positively held to the can end chuck during the operation of double seaming a can end to a can body by reason of the flange 29 moving successively 110 within the gage grooves 40 and 40' of the said can chuck, thereby accurately gaging the seaming grooves 38 and 38' respectively relative to the seam being acted on during the operation of double seaming, and it 115 will be further noted that all thrust strains are removed from the seaming head and that the grooves thereof act properly relatively to the seam being flanged, irrespective of irregularities as to the metal being 120 acted upon.

In the machine herewith illustrated there is only shown one seaming mechanism and one can end chuck operated upon during the action of the rotary head 11, but it is ob- 125 130

vious that any number of can end chucks and seaming heads or mechanism may be employed and thrown into action by the movement of the rotary head 11, and therefore I do not wish to be understood as limiting the invention to the employment of a single seaming head and can end chuck, but any number thereof may be employed consistent with structural practicability.

10 It will be understood that the operating parts of the apparatus are actuated in timed relation, so that the can end chuck is lowered to clamp a can end to a can body, on a can body with an end loosely applied thereto 15 being delivered onto the rotatable can seat 43, and that the seaming head is lowered and moved regularly toward and from the can end chuck after the same has clamped a can end to a can body to which it is to be 20 double seamed.

Having thus described the invention what is claimed as new and desired to be protected by Letters Patent is:—

1. An apparatus for the described purpose, the same comprising means for holding a flanged can and an end to be hermetically seamed to the flange thereof, the same including a can end chuck having formed therein a plurality of circumferentially disposed gage grooves, a seaming roll having formed therein a plurality of seaming grooves and provided with a circumferential flange outwardly projecting therefrom, and rotary means for imparting vertical movement to the can end chuck and to the seaming roll and moving the said roll radially relative to the can end chuck to place the flange of the said roll successively into engagement with the grooves of the can end 35 chuck and the grooves of the said seaming roll successively into engagement with the flange of said can for the hermetic seaming of the end thereto.

2. In an apparatus for the described purpose, the same comprising means for holding a flanged can and an end to be hermetically seamed thereto, the same including a can end chuck having formed therein a plurality of circumferentially disposed gage 50 grooves, a seaming roll having formed therein a plurality of seaming grooves and provided with an outwardly projecting circumferential flange above the said grooves, means for imparting vertical and rotary motion to the can end chuck, and mechanism for imparting vertical movement to the seaming roll and moving the same radially relative to the can end chuck to place the flange thereof successively into and out of engagement with the grooves of the said 60 chuck and the grooves of the said seaming roll successively into engagement with the flange of the can for the seaming of the end thereto.

3. In an apparatus for the described pur-

pose, a can end chuck having formed therein a plurality of gage grooves and adapted for holding a flanged can and an end to be seamed thereto, mechanism for imparting vertical and rotary movement to the said can end chuck, a seaming head carried in operative relation with the can end chuck, a seaming roll carried by said head and having formed therein a plurality of seaming grooves and provided with a circumferential 70 projecting flange, and means for moving said head for successively placing the flange of its seaming roll in horizontal alinement with the gage grooves of the can end chuck and moving the same radially to place its flange 75 successively into and out of engagement therewith, and the seaming grooves thereof successively into engagement with the flange of the can for the seaming of the end thereto.

4. In an apparatus for seaming an end to a can body, the combination with a can end chuck having formed therein a plurality of circumferentially disposed gage grooves, a seaming roll having a plurality of seaming grooves formed therein and provided with 90 an outwardly projected circumferential gage flange, and means for moving said seaming roll axially and radially relative to the can end chuck to place the flange thereof successively into engagement with the gage grooves 95 of the said chuck and the seaming grooves thereof successively into engagement with the flange of a can for the seaming of the end thereto.

5. In an apparatus for the described purpose, means for holding a flanged can and end to be seamed thereto, the same including a can end chuck having formed therein a plurality of gage grooves, rotary mechanisms for actuating said means to cause the can 100 end chuck to clamp and hold a can end to a can body, a seaming head adapted for movement axially and radially with respect to the flanged end of a clamped can, a seaming roll carried by said head and provided with a 110 plurality of seaming grooves and an outwardly projected circumferentially disposed gage flange, and means for moving said seaming head to place the flange of the seaming roll successively into and out of engagement with the gage grooves of the can end 115 chuck and to bring the seaming grooves thereof successively into engagement with the flange of the can for the seaming of the end thereto.

6. In an apparatus for the described purpose, the combination with a rotary and vertically movable can end chuck provided with a plurality of peripheral gage grooves, a seaming roll having formed therein a plurality of seaming grooves and provided with an outwardly projected circumferential gage flange, and mechanism for moving the seaming roll axially and radially with respect to the can end chuck to place the flange thereof 125 130

successively into engagement with the gage grooves of the said chuck.

7. In an apparatus for the described purpose, the combination with rotary means for receiving and clamping cans with ends loosely applied thereto, the same including a can end chuck provided with a plurality of gage grooves therein, devices for delivering cans with ends loosely applied thereto to said means, a seaming roll having formed therein a plurality of peripheral seaming grooves and provided with an outwardly projected circumferential gage flange, and means for moving the seaming roll for placing the gage flange thereof successively into engagement with the gage grooves of the can end chuck and the seaming grooves into engagement successively with the flange of a held can for the hermetic seaming of the end thereto.

8. In an apparatus for the described purpose, the combination with means for receiving and holding a flanged can with an end loosely applied for hermetic seaming thereto, the same including a can end chuck having formed therein peripheral gage grooves in different horizontal planes, a seaming roll provided with an outwardly projecting circumferential gage flange and formed with peripheral seaming grooves in different horizontal planes, and means for moving said seaming roll with respect to the can end chuck to place the gage flange thereof into engagement successively with the grooves of the said chuck and the seaming grooves thereof into engagement successively with the flange of the held can for the seaming of the end thereto.

9. In an apparatus for the described purpose, the combination with mechanism for holding a flanged can with an end to be united loosely applied thereto, the same including a can end chuck with peripheral gage grooves in different horizontal planes, of an auxiliary and radially movable seaming roll provided with an outwardly projected circumferential gage flange and formed with a plurality of peripheral seaming grooves, and means for moving the said seaming roll for successively placing the gage flange thereof into radial alinement with the gage grooves of the can end chuck and moving the same into engagement therewith and the seaming grooves thereof successively into engagement with the flange of a held can for hermetically seaming the end thereto.

10. In an apparatus for the described purpose, the combination with a support provided with a horizontally rotating member for the reception of can bodies with an end loosely applied thereto, means for delivering successively to said member flanged cans with ends loosely applied thereto, a can end chuck having a plurality of gage grooves

formed therein associated with said member and in axial alinement therewith for the clamping of a can with an end loosely applied thereto to the said rotatable member, rotary means for imparting vertical and rotary movement to the can end chuck, an axially and radially movable seaming roll having formed therein a plurality of peripheral seaming grooves and provided with an outwardly projecting circumferential flange, and means for moving said seaming roll to place the gage flange thereof into engagement successively with the gage grooves of the can end chuck and its seaming grooves successively into engagement with the flange of a held can for the double seaming of the end thereto.

11. In an apparatus for seaming ends to can bodies, the combination with a rotatable seat for receiving and supporting can bodies with the ends loosely applied thereto, a can end chuck provided with a plurality of peripheral gage grooves, means for actuating said chuck to clamp the can body with its applied end to the rotatable seat and for imparting rotation thereto, a seaming roll formed with a plurality of peripheral seaming grooves and an outwardly projecting gage flange, and means for moving the said seaming roll axially and radially with respect to the can end chuck to place the gage flange thereof into engagement successively with the gage grooves of the can end chuck and the seaming grooves successively into engagement with the flange of the can for hermetically seaming the end thereto.

12. An apparatus for the described purpose, the same comprising a can end chuck for holding a can end to a can body during the operation of double seaming and having formed therein a plurality of circumferentially disposed gage grooves, rotary means for imparting vertical and rotary movements to the said can end chuck, a seaming roll having formed therein a plurality of seaming grooves and provided with a circumferential flange adapted to be moved successively into and out of engagement with the gage grooves of the can end chuck, and means actuated by the mentioned rotary means for actuating the seaming roll to place the gage flange thereof successively into engagement with the grooves of the can end chuck and the seaming grooves of the said roll successively into engagement with the flange of a clamped can for hermetically seaming of the end cover thereto.

13. In an apparatus for the described purpose, the combination with a vertically movable rotary can end chuck provided with a plurality of peripheral gage grooves, of axially and radially movable seaming means adapted to be moved into engagement successively with the gage grooves of the can end chuck, and devices for actuating said

seaming means for properly positioning the same with respect to the can end chuck.

14. In an apparatus for hermetically sealing can ends to can bodies, the combination with a can end chuck provided with a plurality of peripheral gage grooves, of a seaming roll provided with an outwardly projected gage flange and a plurality of peripheral seaming grooves, and means for actuating the seaming roll to place the gage

flange thereof into and out of engagement successively with the gage grooves of the can end chuck.

In testimony whereof I have signed my name to this specification in the presence of 15 two subscribing witnesses.

AXEL JOHNSON.
